UNITED STATES PATENT OFFICE

148,056

DESIGN FOR A MILK PITCHER

Rolf John Falk, Zanesville, Ohio, assignor to
Shawnee Pottery Company, Zanesville, Ohio, a
corporation of Ohio

Application April 20, 1946, Serial No. 128,809

Term of patent 14 years

(Cl. D44—21)

To all whom it may concern:

Be it known that I, Rolf J. Falk, a citizen of the United States of America, residing at Zanesville, in the county of Muskingum and State of Ohio, have invented a new, original, and ornamental Design for Milk Pitcher, of which the following is a specification, reference being had to the accompanying drawings, forming a part thereof, wherein:

Fig. 1 is a perspective view of a milk pitcher illustrating my new design;

Fig. 2, a perspective view from the other side; and

Fig. 3, a top plan view thereof.

I claim:

The ornamental design for a milk pitcher, as shown.

ROLF JOHN FALK.
